UNITED STATES PATENT OFFICE.

PATRICK A. BAYLESS, OF OKLAHOMA, AND HOWARD D. HENRY, OF EL RENO,
OKLAHOMA.

COLLAPSIBLE DRINKING-CUP.

1,025,606.

Specification of Letters Patent.

Patented May 7, 1912.

Application filed August 27, 1910. Serial No. 579,305.

To all whom it may concern:

Be it known that we, PATRICK A. BAYLESS and HOWARD D. HENRY, citizens of the United States, and residents of Oklahoma city, county of Oklahoma, State of Oklahoma, and El Reno, in the county of Canadian and State of Oklahoma, respectively, have invented certain new and useful Improvements in Collapsible Drinking-Cups, 10 of which the following is a specification, reference being had therein to the accompanying drawing.

This invention relates to drinking cups, and the principal object of the same is to 15 provide a cup that can be folded into a small compass so that the same can be carried in a pocket.

In carrying out the objects of the invention generally stated above it will be understood, of course, that the essential features thereof are necessarily susceptible of changes in details and structural arrangements, one preferred and practical embodiment of which is shown in the accompanying 25 drawings, wherein:—

Figure 1 is a perspective view of the improved cup as it appears when ready to be used. Fig. 2 is a side view of the cup when folded. Fig. 3 is a plan of the blank from 30 which the body of the cup is formed.

Referring to the accompanying drawings by numerals, it will be seen that the improved cup comprises a body 1 that is formed from a single sheet of metal or 35 other resilient sheet material, said sheet being elongated and provided with a central transverse fold line 2. The ends of the sheet are provided with central longitudinal slits 3 which extend toward the fold line 2 and from the ends of said slits, diverging slits 4 extend adjacent to the ends of the 40 said fold line 2. This arrangement of slits and fold line provides the four sides 5 of the body and the inclined bottom surfaces 6.

45 A supporting and edge-sealing frame is provided for the body, said frame being formed of thin flexible sheet metal or other suitable material shaped to provide the strips 7 that overlap and seal the junction 50 of the meeting edges of the sides 5, the short strips 8 that overlap and seal the slits 3, and the divergent strips 9 which extend from the strips 8 and overlap the seal the

divergent slits 4. Said frame is rigidly fastened to the body over the meeting edges 55 thereof, and, being flexible, serve as hinges to allow said body to be opened, as indicated in Fig. 1, or folded as indicated in Fig. 2, so that the same may be placed in a pocket.

It will be seen from the foregoing that 60 the improved cup can be readily folded and placed in an envelop or the like and sealed, so that the same can be kept in a perfectly sanitary condition; also that the same being formed of sheet material, the blank thereof 65 can be quickly and economically produced and then readily "set-up" in operative condition.

What we claim as our invention is:—

In a device of the kind described, a cup 70 formed from a blank comprising a central diamond-shaped portion having a fold line extending from one obtuse angle to the other, said blank further having extensions from the sides of the diamond-shaped portion defined therefrom by fold lines forming the outline of the diamond shaped central portion, each of said extensions having a curved outer edge and being united in pairs along fold lines forming the prolongation of the diagonal line of the diamond 75 extending from one acute angle to the other and having the other edges free inclined toward each other; in combination with a frame formed from a single piece of thin 80 flexible material, said frame comprising a central diamond shaped portion overlapping the fold lines between the central portion of the blank and the extensions, said central portion of the frame having extensions from its acute angles overlapping the 85 fold lines between the adjacent extensions of the blank, said frame further having extensions from the obtuse angles, each of which is folded upon itself to embrace the 90 free edges of the extensions of the blank and unite them in pairs when the blank is folded on the fold line uniting its obtuse angles.

In testimony whereof we hereunto affix our signatures in presence of two witnesses. 100

PATRICK A. BAYLESS.
HOWARD D. HENRY.
